UNITED STATES PATENT OFFICE.

HOWARD B. SHERMAN, OF BATTLE CREEK, MICHIGAN.

DESIGN FOR A METAL STRIP.

45,895.

Specification for Design.

Patented June 2, 1914.

Application filed April 4, 1914. Serial No. 829,716. Term of patent 14 years.

To all whom it may concern:

Be it known that I, HOWARD B. SHERMAN, a citizen of the United States, residing at Battle Creek, in the county of Calhoun and State of Michigan, have invented a certain new, original, and ornamental Design for a Metal Strip; and I hereby declare that the following is a full, clear, and exact description thereof, reference being had to the accompanying drawings, which form part of this specification.

The drawing represents a perspective view of a portion of an ornamental metal strip or ribbon.

The design for an ornamental strip or

metal ribbon comprises a ribbon shaped strip *a* having at intervals a series of annular ornamental bosses or knurls *b* projecting above the plane of the strip and having concave centers *c*.

I claim:

The ornamental design for metal strip, substantially as shown.

In testimony that I claim the foregoing as my own, I affix my signature in presence of two witnesses.

HOWARD B. SHERMAN.
